SHELF SUPPORT COMBINATION AND CABINET

Samuel Hammer, New York, N. Y., assignor to
 United Metal Box Co., Inc., Brooklyn, N. Y.,
 a corporation of New York

Application January 12, 1945, Serial No. 572,475

27 Claims. (Cl. 312—156)

1

The invention relates to a shelf support combination by means of which a shelf may be supported upon vertically disposed side walls. The invention also relates to a combination of supporting side walls, back wall, the shelf supporting means and a shelf. The bracket itself also constitutes a sub-combination of the invention as an article of manufacture. The invention has application with any shelf construction such as bookshelves, kitchen cabinet shelves, in fact wherever shelves are used. The invention is illustrated for use in a bathroom medicine cabinet.

This application is a continuation in part of my application Serial No. 539,462, filed June 9, 1944, now abandoned.

It is an object of the invention to construct a new and novel shelf support combination which is simple in construction and consequently inexpensive to manufacture and which effectively supports a shelf.

Another object of the invention is to construct a shelf support combination in which the shelf locks the bracket to the side wall of the shelf support combination.

Another object of the invention is to construct a shelf support combination in which the bracket may be formed from strip material and its finished form completed by a simple punching operation or a punching and bending operation without waste of material.

A still further object of the invention is to construct a shelf support combination in which a bracket is locked to the side wall of the shelf support combination merely by placing the shelf upon the bracket.

A still further object of the invention is to construct a shelf support combination such that a single construction of cabinet may be used to provide a cabinet having hinges upon either the right or the left hand side merely by turning the cabinet upside down. The shelf supporting combination may be utilized in either position of the box with equal efficacy.

An object of the invention is to provide a shelf support combination which retains the bracket in position upon the side members so that it will not shake loose during transportation or other handling of the cabinet or structure upon which the brackets are mounted.

Another object is to construct a shelf support and side wall combination which utilizes a slot in the side wall to support the bracket and means are provided to enclose the slot against infiltration of dust and dirt which means also serves the purpose of retaining the shelf bracket in

2

position within the slot when a shelf is not carried by the bracket.

Other objects of the invention will be more apparent from the following description taken in connection with the accompanying drawings showing several embodiments of the invention in which:

Figure 1 is a perspective view in reduced size of a cabinet such as is used as a medicine cabinet in a bathroom. The cabinet shows a series of shelves mounted therewith which may be shifted to various positions as desired.

Figure 2 is a partial view of a side wall forming a part of the shelf support combination with shelf supporting brackets of two kinds mounted in initial position upon the side wall and also moved to final position and locked in that position against removal by a shelf so long as the shelf remains upon the bracket.

20 Figure 3 is a horizontal sectional view taken on line 3—3 of Figure 2 through a side wall and a top view of the shelf support combination with a shelf bracket in initial position.

Figure 4 is a horizontal sectional view taken on line 4—4 of Figure 2 with the shelf omitted through a side wall showing the shelf bracket in final position thereon.

Figure 5 is a sectional view taken on line 5—5 of Figure 2 of a side wall showing a shelf bracket of different construction from that shown in Figures 3 and 4 with the bracket in final position.

Figure 6 is a sectional view taken on line 6—6 of Figure 2 of a side wall showing the bracket of Figure 5 in its initial position.

35 Figure 7 is a vertical section taken on line 7—7 of Figure 2 showing the bracket of Figures 3 and 4 particularly and of Figures 5 and 6 in final position upon the side wall and a shelf supported on the bracket.

40 Figure 8 is a horizontal sectional view through a side wall having an outwardly directed channel for the shelf support combination with a third type of bracket retained upon the side wall, the bracket being in its final position.

45 Figure 8a is a modification of Figure 8, with the channel 44 directed inwardly.

Figure 9 is a view in elevation of the side wall and the bracket of the construction shown in Figure 8.

50 Figure 10 is a vertical sectional view of another bracket construction in which a single central projection is used upon the bracket which requires a deeper inwardly directed channel in the side wall.

Figure 10a is the side elevation of the bracket of Figure 10.

Figure 11 is a partial plan view of a side wall such as for a bath room cabinet showing a shelf bracket or support inserted into initial position in a slot in the side wall and also showing a support which has been moved forward so that it is retained upon the side wall.

Figure 12 is a horizontal section through the side wall of Figure 11 showing the shelf support retained in position upon the side wall and removably secured in that position against inadvertent removal.

Figure 13 is a horizontal section through the side wall of Figure 11 showing a shelf support laterally inserted into the slot into its initial position.

Figure 14 is a horizontal section through the side wall of Figure 11 and showing the shelf support partially advanced towards its final position upon the side wall.

The shelf support combination to be described herein provides a structure for supporting a shelf which is secure and firm yet is easily manipulated for mounting a shelf or the shifting of a shelf to a different level. The simplicity of the shelf support combination also makes it inexpensive to manufacture.

The construction also permits one construction of cabinet to be manufactured which may be used with the hinge means on either side of the cabinet. For example if a cabinet with the door hinged on the right hand side is wanted the cabinet is mounted in that position and if it is desired to have the door hinge means on the left side, the cabinet is merely turned upside down and the shelf support combination is equally effective and as easily installed or shifted within the cabinet in this reversed position. The one construction of cabinet can be used with equal facility in either position.

The shelf support combination is shown particularly as used in a so-called medicine cabinet mounted in a wall in a bathroom. The cabinet 10 has side walls 11 and 12 and a back 13. A door 14 is mounted upon hinge means 15 on the right-hand side of the cabinet. If it is desired to have the hinge means on the left-hand side, the cabinet only need be turned upside down and reversing the position of the shelf supporting brackets.

Each side wall 11 and 12 of the cabinet is provided with an inwardly directed channel 19 which because it is inwardly directed furnishes a raised ridge on the inside of the cabinet. The channel or ridge of each side wall has at least one horizontally extending slot 20 therein and preferably a series of such slots are provided in different positions so that the shelf supporting brackets may be placed in any desired level along the side wall or within the cabinet. The slot 20 has a recess 21 preferably on each side of the slot for reasons which will appear more fully hereinafter. The recesses may be located anywhere along the slot depending upon the extent of forward movement of the bracket desired.

A shelf supporting bracket 24 is secured to the side within the slot 20. The bracket shown in Figure 3 is made from a flat piece of strip material having parallel sides. A tongue 25 is fastened at the edge of the strip as by slitting or punching the edge of the bracket inwardly and horizontally or parallel with the edge of the bracket. Preferably a similar tongue is provided upon each side of the bracket so that a

bracket may be used interchangeably on either the right or left-hand side of the cabinet. The tongue carries a projection 26 which is preferably struck or pressed outwardly into the tongue and hence is resiliently or yieldably mounted by virtue of the resiliency of the tongue. The tongue or projection also may have an inclined or angular end 27 to provide a camming surface the purpose of which will appear more fully herein-after. The projection may be struck downwardly or upwardly as desired.

The forward end of the bracket may carry a shoulder 28. The shoulder serves as a stop for a shelf and also serves to lock the bracket in position on the side wall as will appear herein-after. In the form illustrated the shoulder is curved so as to receive a curved end or edge of a shelf such as the glass shelf 29. With such arcuate form of shoulder the front edge of the shelf is fixed in position against vertical displacement.

The bracket is mounted on a side wall by slipping the edge of the bracket into the slot 20 with the projection 26 upon the tongue 25 projected through a recess 21 to the other side of the wall of the channel. It will be noted that the projection in the lower face of the bracket requires only the lower recess for insertion of the bracket in the slot, however when the cabinet is turned upside down as previously explained then the recess which heretofore was in the upper position is now in the lower position and passes the projection to the other side of the wall.

The channel is provided for several reasons 35 one of which is to enable a bracket with straight parallel sides to be used. Hence inexpensive strip material may be used for the bracket without machining the side thereof. The edge of the bracket engages the inner surface of the side wall and yet the projection and tongue upon the edge of the bracket is on the other side of the wall within the channel. Preferably the projection or tongue has a width or dimension a little greater than the dimension from the inner face of the side wall 11 to the outer face 30 of the channel. Actually the inner edge of the projection may be spaced from the edge of the bracket a distance slightly greater than the dimension between the inner face of the side wall and the outer face of 45 the channel. Hence when the bracket is moved forwardly in the slot, the camming edge 27 on the projection and tongue resiliently engages the opposite face of the side wall or channel surface so that the bracket is secured within the slot by the projection and the resilient tongue supports it tightly and without shaking.

The channel serves another purpose, in addition to enabling the edges of the bracket to be straight edges and hence can be made from strip material, in that the laterally extending sides 60 33 thereof at the slot give relatively wide support for the bracket. This support is several times that which would be afforded by the edges of the slot alone.

65 The channel serves still another purpose in that the forward laterally extending side of the channel is engaged by the projection 26 which limits the forward movement of the bracket. The channel is made, therefore, with a width and location such that the forward side of the channel is properly located to serve as a stop for the bracket.

If a shelf 29 now has its front end positioned in the semi-circular shoulder 28 of the bracket mounted upon each side wall and the back edge

pivoted downwardly so that the shelf rests upon the pair of brackets, the rear edge of the shelf is closely adjacent or may engage the rear wall 13 of the cabinet. With the shelf in position it will be observed that the bracket cannot be moved rearwardly because the back edge of the shelf would prevent this movement by engaging the back wall and consequently the brackets are locked in position by the shelf. The back wall of the cabinet serves also as a shoulder or abutting means for the rear edge of the shelf which locks the bracket upon the side wall. In the event that the structure is not a cabinet with a back wall which serves as an abutment, suitable abutting means may be provided at the back end of the side wall to serve as a stop for the shelf in the same manner that the back wall serves as an abutting means.

A slightly different form of bracket is shown in the upper two brackets of Figure 2 which are also shown in plan view in Figures 5 and 6. The bracket 35 may be used with the same channel side wall slot and recess. It also may have the shoulder 28. The bracket 35 however uses a projection 36 which is rigid or non-resilient in that it is struck downwardly at least upon one edge of the bracket and both ends of the projection are integral with the bracket. This projection may have a camming edge 37 in order to make it easy to move the bracket to its final position with the bracket engaging the outer or opposite wall of the channel. Like the projection 26 of Figures 3 and 4, this projection 36 also may be slightly wider than the dimension between the inner face of the side wall and the outer face of the channel so that the bracket is firmly held in position in the slot and side wall. In this construction with a rigid projection the resiliency or flexibility in the channel or side wall at the slot is utilized to hold the bracket firmly.

A different form of bracket is illustrated in Figures 8 and 9. In this construction the side wall 40 preferably has a channel 41 formed in the side wall which may be either inwardly or outwardly directed, that illustrated being outwardly directed, in order to provide laterally extending edges for greater support or stability for the bracket. The channel in this construction is not essential and serves no other purpose than to supply additional support for the bracket and increase the rigidity of the side wall. The side wall carries at least one and preferably a plurality of horizontal and vertically spaced slots 42 to receive a bracket.

The bracket 45 is received in the slots 42 which bracket does not have two straight parallel edges as in the brackets of Figures 2 to 6. This bracket has a projection 46 preferably extending from each side thereof one of which passes through the slot depending upon whether the bracket is used upon a left or right-hand side wall. The forward end of the projection carries a tongue 47 which engages the outer side of the side wall 40 when the bracket is moved forward in the slot. The tongue may be bent inwardly slightly to resiliently engage the side wall and thereby provide a firm support for the bracket. The projection 46 preferably is provided upon each side of the bracket so that it may be used in a left-hand side wall or a right-hand side wall. This bracket may have a shoulder 48 at the forward end thereof to engage the front end of a shelf which shoulder serves as a stop for the shelf and the shelf serves to lock the bracket in forward position of the slot and on a side wall in the same manner that the

shelf 49 of Figure 2 serves to lock the brackets upon the side wall.

Figure 10 shows a construction in which a relatively deeper channel 51 is provided in the side wall than that illustrated in Figures 1 through 7 and 12 through 14. The channel has a slot 52 and recess 53 upon each side of the slot. The bracket 54 is received in the slot and slideable therein. Because the channel is deeper the bracket needs only one centrally disposed projection 55 which projection may be of the tongue type of Figures 3 and 4 or may be of the rigid type of Figures 5 and 6.

In Figures 11 through 14 a construction is shown which adds further features to the construction shown in the other figures. The slots extend through the wall of the cabinet and although the shelf bracket or support largely fills the slot there are still spaces which would permit dust and dirt from within the wall to seep through the spaces in the slot into the cabinet. It is desirable therefore to seal or enclose the channel in the side wall which also encloses the slots from communication with the interior walls of the building. This seal or enclosure comprises a plate 59 which is secured to the outer face of the side wall at its edge 60 such as by welding. The other edge 61 is a free edge in that it is not secured but merely rests flatly against the outer face of the side wall. The enclosing plate has a projection 61 which is preferably a ridge extending the full length thereof and forming a locking or retaining ridge. The plate 59 in being secured at one edge only provides a resilient or spring latch in the projection 62 for releasably retaining the shelf bracket against vibrating loose or inadvertent removal from the slot when handled or in transit.

The shelf bracket has an indentation or recess 63 upon each side edge of the bracket and preferably a second indentation 64 spaced therefrom. The indentation 63 is located in such a position that when the projection 26 of the bracket is inserted through the opening 21, the plate projection 62 is opposite the indentation 64 so that there is no resistance to the lateral insertion of the bracket into the slot. When the bracket is moved forward as illustrated in Figure 14 in order to secure the bracket within the slot the slot enclosing plate 59 yields, the indentation having a camming action upon the projection 62. When the bracket has been moved to its forward position, the projection 26 engages the end of the channel and the indentation 63 comes opposite the projection 62 which snaps thereinto and holds the bracket against inadvertent rearward movement which may release the bracket from the slot. The bracket is therefore removably retained within the slot so that it will not jar loose when the cabinet is in transit or being handled. The plate 59 therefore serves a double purpose in enclosing or sealing the slots from the interior of the wall and in forming a retaining means for the bracket.

The invention is presented to fill a need for improvements in a shelf support combination and cabinet. It is understood that various modifications in structure, as well as changes in mode of operation, assembly, and manner of use, may and often do occur to those skilled in the art, especially after benefiting from the teachings of an invention. Hence, it will be understood that this disclosure is illustrative of preferred means of embodying the invention in useful form by explaining the construction, operation and advantages thereof.

What is claimed is:

1. A shelf support combination comprising a side wall having a horizontal slot therein, the ends of the slot being spaced from the edges of the side wall, a bracket for a shelf received in the slot and movable therein in the direction of the slot, the slot having a width approximately the same as the thickness of the bracket to support the same, the edge of the bracket engaging the inner face of the side wall, and means carried by the bracket insertable laterally through the slot and engaging the opposite side of the side wall upon movement of the bracket in the slot in the direction thereof to hold the bracket to the side wall.

2. A shelf support combination comprising a side wall having a horizontal slot therein, the ends of the slot being spaced from the edges of the side wall, a bracket for a shelf received in the slot and movable therein in the direction of the slot, the slot having a width approximately the same as the thickness of the bracket to support the same, the edge of the bracket engaging the inner face of the side wall, and means carried by the bracket insertable laterally through the slot and engaging the opposite side of the side wall upon movement of the bracket in the slot to hold the bracket to the side wall, and a shoulder carried by the bracket at its forward end to form a lock for the bracket against movement in the direction of the slot for releasing the same and to form a stop for a shelf.

3. A shelf support combination comprising a side wall having a horizontal slot therein and a recess upon both sides of the slot, the ends of the slot being spaced from the edges of the side wall, a bracket for a shelf received in the slot and movable therein in the direction of the slot, the slot having a width approximately the same as the thickness of the bracket to support the same, the edge of the bracket engaging the inner face of the side wall, and means projecting above at least one face of the bracket insertable laterally through the recess and engaging the opposite side of the side wall upon movement of the bracket in the slot to hold the bracket to the side wall.

4. A shelf support combination comprising a side wall, a vertically extending and inwardly directed channel in the side wall, the channel having at least one horizontally extending slot providing lateral edges at the sides of the channel, a bracket for a shelf received in the slot and movable therein in the direction of the slot, the slot having a width approximately the same as the thickness of the bracket to support the same, the edge of the bracket engaging the inner face of the side wall, the bracket engaging the lateral edges of the channel in the slot for additional support, and means carried by the bracket insertable laterally through the slot and engaging the opposite side of the side wall upon movement of the bracket in the slot in the direction of the slot to hold the bracket to the side wall.

5. A shelf support combination comprising a side wall, a vertically extending and inwardly directed channel in the side wall, the channel having at least one horizontally extending slot providing lateral edges at the sides of the channel and a recess in at least one side of the slot, a bracket for a shelf received in the slot and movable therein in the direction of the slot, the slot having a width approximately the same as the thickness of the bracket to support the same, the edge of the bracket engaging the inner face of the side wall, the bracket engaging the lateral

edges of the channel in the slot for additional support, and means struck up on the bracket insertable laterally through a recess and engaging the opposite side of the side wall upon movement of the bracket in the slot in the direction thereof to hold the bracket to the side wall, the side of the channel being located to serve as a stop for the struck up means and the bracket.

6. A shelf support combination comprising a side wall, a vertically extending and inwardly directed channel in the side wall, the channel having at least one horizontally extending slot providing lateral edges at the sides of the channel and a recess in at least one side of the slot, a bracket for a shelf received in the slot and movable therein in the direction of the slot, the slot having a width approximately the same as the thickness of the bracket to support the same, the edge of the bracket engaging the inner face of the side wall, the bracket engaging the lateral edges of the channel in the slot for additional support, means carried by the bracket extending above the surface thereof and insertable laterally through a recess and engaging the opposite side of the side wall upon movement of the bracket in the slot in the direction thereof to hold the bracket to the side wall, the side of the channel serving as a stop for the bracket means and the bracket, and shoulder carried by the bracket at its forward end to form a lock for the bracket and a stop for a shelf.

7. A shelf support combination comprising a side wall, a vertically extending and inwardly directed channel in the side wall, the channel having at least one horizontally extending slot providing lateral edges at the sides of the channel and a recess in at least one side of the slot, a bracket for a shelf received in the slot and movable therein in the direction of the slot, the slot having a width approximately the same as the thickness of the bracket to support the same, the edge of the bracket engaging the inner face of the side wall, the bracket engaging the lateral edges of the channel in the slot for additional support, the bracket having straight parallel edges which engage the side wall, and means carried by the bracket which extends above the surface thereof and insertable laterally through a recess and engages the opposite side of the side wall upon movement of the bracket in the slot in the direction thereof to hold the bracket to the side wall.

8. A shelf support combination comprising a side wall, a vertically extending and inwardly directed channel in the side wall, the channel having at least one horizontally extending slot providing lateral edges at the sides of the channel and a recess in at least one side of the slot, a bracket for a shelf received in the slot and movable therein in the direction of the slot, the slot having a width approximately the same as the thickness of the bracket to support the same, the edge of the bracket engaging the inner face of the side wall, the bracket engaging the lateral edges of the channel in the slot for additional support, the bracket having straight parallel edges, and means struck up at least on one edge of the bracket which extends through a recess and engages the opposite side of the side wall upon movement of the bracket in the slot in the direction thereof to hold the bracket to the side wall, the struck up means having a width approximating the depth of the channel.

9. A shelf support combination comprising a side wall, a vertically extending and inwardly

directed channel in the side wall and the channel having at least one horizontally extending slot providing lateral edges at the sides of the channel and a recess in at least one side of the slot, a bracket for a shelf received in the slot and movable therein in the direction of the slot, the bracket engaging the lateral edges of the channel in the slot to give additional support to the bracket, the bracket having straight parallel edges, a resilient tongue at least upon one edge of the bracket, and a projection struck up on the tongue which extends through a recess and engages the opposite side of the side wall upon movement of the bracket in the slot to hold the bracket to the side wall.

10. A cabinet and shelf support combination comprising a cabinet having a pair of side walls, each side wall having at least one horizontal slot therein, the ends of the slot being spaced from the edges of the side wall, and a recess upon both sides of each slot, a door, hinges mounting the door upon one side of the cabinet, at least one shelf for the cabinet, a pair of brackets for each shelf one received in a slot in each side wall and movable therein in the direction of the slot, the slot having a width approximately the same as the thickness of the bracket to support the same, the edge of the bracket engaging the inner face of the side wall, and means projecting above the surface of each bracket extending through a slot and its recess and engaging the opposite side of the side wall upon movement of the bracket in the slot in the direction thereof to hold the bracket to the side wall whereby the cabinet may be mounted so that the hinges are upon the left or the right side of the cabinet.

11. A cabinet and a shelf support combination comprising a cabinet having a pair of side walls, each side wall having an inwardly directed channel, each channel having at least one horizontal slot therein and a recess upon both sides of the slot, the ends of the slot being spaced from the edges of the side wall, a door, hinges mounting the door upon one side of the cabinet, at least one shelf for the cabinet, a pair of brackets for each shelf one received in a slot in each side wall and movable therein in the direction of the slot, the slot having a width approximately the same as the thickness of the bracket to support the same, the edge of the bracket engaging the inner face of the side wall, and means projecting above one surface of each bracket extending through the recess and engaging the opposite side of the side wall of the channel upon movement of the bracket in the slot in the direction thereof to hold the bracket to the side wall whereby the cabinet may be mounted so that the hinges are upon the left or the right side of the cabinet.

12. A cabinet and shelf support combination comprising a cabinet having a pair of side walls, and a back wall, a vertically extending and inwardly directed channel in each side wall, each channel having at least one horizontally extending slot providing lateral edges at the sides of the channel and a recess in at least one side of the slot, a pair of brackets for each shelf one received in a slot in each side wall and movable therein in the direction of the slot, each bracket engaging the lateral edges of its channel in the slot for additional support, means carried by each bracket projecting above the surface thereof which extends through a recess and engages the opposite side of the side wall upon movement of

the bracket in the slot in the direction thereof to hold the bracket to the side wall, the channel having a width such that the side of the channel serves as a stop for the projecting means and the bracket, a shoulder carried by the bracket at its forward end which is spaced from the back wall when the bracket is in forward position a distance approximating the width of a shelf, and a shelf placed upon each pair of brackets to form a lock for the bracket and a stop for the shelf.

13. A shelf support combination comprising a side wall having at least one horizontal slot therein, a bracket for a shelf received in the slot and movable therein in the direction of the slot, and a forwardly extending tongue carried upon the side of the bracket extending through the slot and engaging the opposite side of the side wall upon movement of the bracket in the slot in the direction thereof to hold the bracket to the side wall.

14. A shelf support combination comprising a side wall having at least one horizontal slot therein, a bracket for a shelf received in the slot and movable therein in the direction of the slot, a tongue carried upon the side of the bracket extending through the slot and engaging the opposite side of the side wall upon movement of the bracket in the slot in the direction thereof to hold the bracket to the side wall, the end of the slot forming a stop for the bracket, and a shoulder carried by the bracket forming a lock for the bracket and a stop for the shelf.

15. A shelf support combination comprising a side wall having at least one horizontal slot therein and a recess at least upon one side of the slot, a bracket for a shelf received in the slot and movable therein in the direction of the slot, the bracket having parallel edges and a rigid projection struck up carried at least at one edge of the bracket so that both ends are integral with the bracket, the projection extending through the recess and engaging the opposite side of the side wall upon movement of the bracket in the slot to hold the bracket to the side wall.

16. A shelf support comprising a bracket having straight parallel side edges and straight end edges, a projection struck out upon the face of the bracket and within the boundaries of the edges of the bracket, and the bracket being otherwise flat between its ends.

17. A shelf support comprising a bracket having straight parallel edges and straight end edges, a projection formed between the parallel edges by striking outwardly an edge portion of at least at one parallel edge of the bracket, a shoulder carried by the bracket at its forward end to form a lock for the bracket and a stop for a shelf, and the bracket being otherwise flat between its ends.

18. A shelf support comprising a bracket formed from strip material and having straight parallel edges and straight end edges, a projection struck up at an edge portion between the parallel edges at least at one parallel edge of the bracket, the projection having both ends integral with the strip material, a shoulder carried by the bracket at its forward end to form a lock for the bracket and a stop for a shelf, and the bracket being otherwise flat between its ends.

19. A shelf support comprising a bracket having straight parallel edges, a resilient tongue formed at least at one edge of the bracket, an angular portion at the end of the tongue to form

11

a camming edge, and a projection struck outwardly on the tongue.

20. A shelf support comprising a bracket of strip material having straight parallel edges, a resilient tongue formed between the edges of the strip material and a projection struck outwardly from the face of the bracket and on the tongue.

21. A shelf support combination comprising a side wall having a slot therein, the ends of the slot being spaced from the edges of the side wall, a bracket for a shelf received in the slot and movable therein, means carried by the bracket extending through the slot and engaging the opposite side of the side wall upon movement of the bracket in the slot in the direction thereof to hold the bracket to the side wall, the slot having a width approximately the same as the thickness of the bracket to support the same, the edge of the bracket engaging the inner face of the side wall, and means to resiliently retain the bracket in its moved position against retractive movement.

22. A shelf support combination comprising a side wall having at least one slot therein, a bracket for a shelf received in the slot and movable therein, means carried by the bracket extending through the slot and engaging the opposite side of the side wall upon movement of the bracket in the slot to hold the bracket to the side wall, a plate secured to the side wall enclosing the slots, and means carried by the plate to resiliently retain the bracket in its moved position.

23. A shelf support combination comprising a side wall, a vertically extending and inwardly directed channel in the side wall, the channel having at least one horizontally extending slot providing lateral edges at the sides of the channel, a recess in at least one side of the slot, a bracket for a shelf received in the slot and movable therein, the slot having a width approximately the same as the thickness of the bracket to support the same, the edge of the bracket engaging the inner face of the side wall, the bracket engaging the lateral edges of the channel in the slot for additional support, means carried by the bracket extending through the recess and engaging the opposite side of the side wall upon movement of the bracket in the slot to hold the bracket to the side wall, and means releasably retaining the bracket in its moved position.

24. A shelf support combination comprising a side wall, a vertically extending and inwardly directed channel in the side wall, the channel having at least one horizontally extending slot providing lateral edges at the sides of the channel, a recess in at least one side of the slot, a bracket for a shelf received in the slot and movable therein, the bracket engaging the lateral edges of the channel in the slot for additional support, means carried by the bracket extending through the recess and engaging the opposite side of the side wall upon movement of the bracket in the slot to hold the bracket to the side wall, a plate secured to the outer faces of the side wall over the channel to enclose the slots, and means carried by the plate to releasably retain the bracket at its moved position.

25. A shelf support combination comprising a side wall, a vertically extending and inwardly directed channel in the side wall, the channel having at least one horizontally extending slot providing lateral edges at the sides of the channel, a recess in at least one side of the slot, a bracket for a shelf received in the slot and mov-

12

able therein, the bracket engaging the lateral edges of the channel in the slot for additional support, means carried by the bracket extending through the recess and engaging the opposite side of the side wall upon movement of the bracket in the slot to hold the bracket to the side wall, a plate secured to the outer face of the side wall at one edge only so that the other edge is free and in contact with the side wall to enclose the slots, a projection carried by the plate and engaging the bracket to releasably retain the same at its moved position.

26. A shelf support combination comprising a side wall, a vertically extending and inwardly directed channel in the side wall, the channel having at least one horizontally extending slot providing lateral edges at the sides of the channel, a recess in at least one side of the slot, a bracket for a shelf received in the slot and movable therein, the bracket engaging the lateral edges of the channel in the slot for additional support, a pair of spaced notches in the edges of the bracket, means carried by the bracket extending through a recess and engaging the opposite side of the side wall upon movement of the bracket in the slot to hold the bracket to the side wall, a plate secured to the outer face of the side wall at one edge only so that the other edge is free and in contact with the side wall to enclose the slots, a longitudinally extending projection carried by the plate and engaging one notch upon lateral insertion of the bracket in the slot and engaging the other notch in the moved position of the bracket to releasably retain the bracket against movement.

27. A cabinet and shelf support combination comprising a cabinet having a pair of side walls and a back wall, a vertically extending and inwardly directed channel in each side wall, each channel having at least one horizontally extending slot providing lateral edges at the sides of the channel and a recess in at least one side of the slot, a pair of brackets for each shelf one received in a slot in each side wall and movable therein, each bracket engaging the lateral edges of its channel in the slot for additional support, means carried by each bracket which extends through a recess and engages the opposite side of the side wall upon movement of the bracket in the slot to hold the bracket to the side wall, the channel having a width such that the side of the channel serves as a stop for the means for holding the bracket and the bracket, a shelf placed upon each pair of brackets, and means cooperating between the bracket and the shelf when the bracket is in forward position to lock the bracket in its forward position.

SAMUEL HAMMER.
